UNITED STATES PATENT OFFICE.

EMIL F. NORELIUS, OF PEORIA, ILLINOIS, ASSIGNOR TO HOLT MANUFACTURING COMPANY, OF PEORIA, ILLINOIS, A CORPORATION OF CALIFORNIA.

TRACK-CHAIN.

1,258,601.

Specification of Letters Patent.

Patented Mar. 5, 1918.

Application filed September 30, 1914. Serial No. 864,253.

To all whom it may concern:

Be it known that I, EMIL F. NORELIUS, a citizen of the United States, residing at Peoria, in the county of Peoria and State of Illinois, have invented a certain new and useful Improvement in Track-Chains, of which the following is specification.

My invention relates to improvements in endless, flexible, self-laying track chains and has for one object to provide a new and improved type of chain which will be durable, cheap, convenient and easily assembled. It is illustrated diagrammatically in one form in the accompanying drawing, wherein—

15 Figure 1 is a detailed side elevation of a portion of the endless, flexible, self-laying truck with parts omitted;

Fig. 2 is a side elevation in part section on an enlarged scale of a single link;

20 Fig. 3 is a plan view thereof;

Fig. 4 is a section on the line 4—4 of Fig. 3;

Fig. 5 is a section on the line 5—5 of Fig. 3;

25 Fig. 6 is a section on the line 6—6 of Fig. 2.

Like parts are indicated by like letters throughout the several figures.

A is an idler wheel; A¹ a driving sprocket wheel and A² a roller supporting wheel of an endless, flexible, self-laying truck. The remaining parts of the truck are omitted for the sake of clearness. These wheels 30 guide and drive respectively and are surrounded and supported by the endless, flexible, self-laying track chain which chain is made up of a series of pivotally connected links having on one side a tread ground contacting surface and on the other side the

35 track forming surface along which the truck rolls laying down and picking up the chain as it travels or progresses in the well-known manner. This chain is made up of a series of links which together with their connection are illustrated in Figs. 2 to 6 inclusive.

40 B is a tread or ground contacting surface. It is corrugated as indicated and has upwardly curved sides B¹ and downwardly extending integral cleats or teeth B² and carries on its back integral therewith link members B³, B⁴. These link members are recessed or apertured as at B⁵ for lightness and to prevent clogging of material. The link members B³, B⁴ are provided at one end 45 with inwardly extending hubs B⁶, B⁶ ap-

ertured as at B⁷. At the other end are offsets as at B⁸, B⁹ and provided with hubs B¹¹, B¹² apertured as at B¹³. The offsets B⁸, B⁹ are of such depth that the distance between the outside of the surface of the hubs B⁶, B⁶ respectively is sufficiently less than the distance between the inside surface or ends of the hubs B¹¹, B¹² to permit insertion of the hubs B⁶, B⁶ between the hubs B¹¹, B¹². The tread portion B is bounded at one end by a curved extension C located beneath the hubs B⁶, B⁶ and is concentric with and tied by the web C¹. It is bounded at the other end by a broken curved member C² beneath and concentric with the hubs B¹¹, B¹² and integral with the ends of the link. This member is cut away as at C³, C⁴ to provide a central curved portion or tongue D¹ which is adapted to be inserted between the hubs B⁶, B⁷ and the portion C and to permit rotation of the two adjacent links without interference by the web C¹ so as to provide a closure between the top and bottom of the series of links.

D is a sleeve forced into the hubs B⁶, B⁶ through the aperture B⁷ and overlying the tongue D¹ which in effect is part of the curved portion C² the width of said tongue D¹ being equal to the distance between the hubs B⁶, B⁶. D² is a pin adapted to be forced into the sleeve D and engage the hubs B¹¹, B¹² through the aperture B¹³. It will be noted that the hub B¹² is recessed as at D³ to engage the offset head D⁴ on the pin D¹. D⁵ is a cotter pin introduced into the opposed end of the pin D¹ to hold the pin against longitudinal displacement.

The use and operation of my invention are as follows:

The combined two-part track link and tread section are cast in the form as indicated. A hardened steel bushing or sleeve is forced into the large aperture in one end of the track links. The link or tread sections are assembled on a board or other suitable manner; the broad curved portion on the left-hand end overlying the narrow portion on the right hand and engaged beneath the hub containing sleeve and the sleeve itself. The pin is then forced through the two sets of hubs and bearing at its center on the positioned sleeve or bushing. The offset head on the pin engaging the recess on one of the outside hubs prevents rotation of the pin with respect to the outside link and thus ro-

tation takes place within the bearing and since the bearing and sleeve are both hardened a minimum of wear can take place. The tread surface itself thus forms a tie to bind and steady and hold in parallelism the two parallel links, and thus the bearing sleeve may be designed with respect to hardness and durability of the bearing element only and need not have any peculiar strength 10 against twisting or bending and of course since it does not have to submit to any bending or twisting strains the bearings remain parallel and accurate and wear is thus minimized.

15 I claim:

1. A tread link section comprising two substantially parallel track links having alined sleeve-receiving openings at their proximate ends, means for connecting said links together, a bearing sleeve forced into said openings from one side of the links and held against rotation relatively to said links, and a pin adapted to be mounted in the opposite proximate ends of the links and to be 20 inserted in the bearing sleeve of an adjacent link, said pin when assembled being rigid
2. A combined track and tread link section comprising two substantially parallel track links having alined sleeve-receiving openings at their proximate ends, a tread web integral with the links and connecting them together, a bearing sleeve forced into said opening from one side of the links and held against rotation relatively to said links, and a pin adapted to be mounted in the opposite proximate ends of the links and to be inserted in the bearing sleeve of an adjacent link, said pin when assembled being rigid 30 relatively to the link in which it is mounted but movable in the bearing sleeve of the adjacent link.

35 2. A combined track and tread link section comprising two substantially parallel track links having alined sleeve-receiving openings at their proximate ends, a tread web integral with the links and connecting them together, a bearing sleeve forced into said opening from one side of the links and held against rotation relatively to said links, and a pin adapted to be mounted in the opposite proximate ends of the links and to be inserted in the bearing sleeve of an 40 adjacent link, said pin when assembled being rigid relatively to the link in which it is mounted but movable in the bearing sleeve of the adjacent link.

45 In testimony whereof, I affix my signature in the presence of two witnesses this 21st day of Sept. 1914.

EMIL F. NORELIUS.
